UNITED STATES PATENT OFFICE

FRANK J. REICHMANN, OF CHICAGO, ILLINOIS

TELEPHONIC RECEIVER

Application filed February 18, 1925, Serial No. 9,943. Renewed April 25, 1929.

My invention relates to telephonic receivers or transmitters, and in most of its aspects relates to types of such apparatus in which a diaphragm is separated from adjacent magnet poles by an air space and in which the appliance is adjusted by varying this air space. Generally speaking, my invention aims to provide an unusually compact and inexpensive construction of a telephonic receiver or transmitter of this general class, and also aims to provide a novel magnet spool, core and permanent magnet assembly.

Referring to some of its more particular objects my invention provides an apparatus of this class in which the adjustment is affected by bodily moving the diaphragm-actuating mechanism with respect to the diaphragm, and also provides means for guiding the actuating mechanism during such movement so as to maintain the effective magnet pole ends parallel to the diaphragm and so as to prevent the mechanism from rotating with respect to its support during such adjusting movement.

My invention also provides a receiver or transmitter construction advantageously employing a laminated core for its magnet spools, provides simple means for securing each magnet spool in predetermined position with respect to the core without employing auxiliary fastening means, and provides each magnet core with an extension directly engaging a pole of the permanent magnet. It also provides an assembly in which the permanent magnet, magnet spools, core and core extensions are all simultaneously secured to a supporting element, and in which such an assembly can readily be constructed in a compact form with the magnet spools disposed between the poles of a horseshoe magnet. My invention also provides simple means for limiting the extent to which each magnet spool core is slid through the bore of the corresponding wire-wound magnet spool, aims to provide laminated core members, and simple means for wedging the cores in the bores of the corresponding magnet spools and utilizes the resiliency of the laminations for preventing a loosening of the clamping means which se-

cure the electro-magnets to the supporting element.

In some additional objects, my invention provides spring means for moving the actuating mechanism in one direction with respect to the diaphragm, together with means operable from outside the casing of the appliance for moving the mechanism in the opposite direction; and provides means for taking up any lost motion in the said exteriorly operable adjusting means. Furthermore, my invention provides a convenient mounting for the wire terminals and a wire inlet adjacent to these terminals, provides simple means for preventing the mechanism from rotating so as to move the wire terminals out of their proper relation to the said inlet, and also provides simple means for preventing the spring from contacting with the wire terminals. Still further and also more detailed objects will appear from the following specification and from the accompanying drawings, in which

Fig. 1 is an elevation of a telephonic receiver embodying my invention with a part of the casing broken away.

Fig. 2 is an enlarged plan view of the same embodiment, with the cover of the casing, the diaphragm and the washer between the diaphragm and the cover removed.

Fig. 3 is a vertical section taken through the complete apparatus along the line 3—3 of Fig. 2.

Fig. 4 is a fragmentary section taken at right angles to Fig. 3 through the lower part of the apparatus.

Fig. 5 is an enlarged vertical section taken along the line 5—5 of Fig. 2 through one of the wire-carrying magnet spools and its core and the adjacent parts.

Fig. 6 is an enlarged perspective view of one of the laminated core members as it appears when detached.

While all the objects of my invention may be embodied with equal facility in telephonic receivers and transmitters of various types, my invention is particularly adapted for the construction of so-called loud speakers as employed in connection with radio receiving apparatus. I am therefore illustrating and

describing it in such a connection, although I do not wish to be limited to any particular employment of the various novel features here disclosed.

5 With the illustrated embodiment positioned according to the drawings, this includes an upwardly open and substantially cup-shaped casing having a lateral wall 1 provided with a wire inlet 2. Extending 10 across the mouth of the casing is a diaphragm 3 which is held in place by a cover 4, desirably with a washer 5 interposed between the cover and the adjacent part of the casing, to which part 15 the cover is attached by screws 6. The cover has a suitable tone outlet, here shown in the form of an upwardly extending tube 7 which is threaded so that the small end 8 of a suitable horn may be attached to the same when 20 the apparatus is to be used as a receiver, or so that a mouthpiece can be attached when the apparatus is to be used as a transmitter.

To actuate the diaphragm 3 when my apparatus is used as a receiver, or to be actuated by it when the apparatus is used as a transmitter, I provide an electro-magnetic mechanism secured to the horizontal top 9 of a plunger which has a vertical stem 10 extending slidably through the bottom 11 of the 30 casing. The actuating mechanism includes a pair of soft iron cores 12 each of which extends vertically through the bore of a spool 13 carrying a winding 14 of wire, and each of which cores has at its lower end an extension 15 which has a portion disposed between the plunger top or mechanism-supporting element 9 and the one pole of a permanent magnet 16. This magnet is desirably of a horseshoe formation, thereby permitting both magnet spools to be disposed within its mouth and permitting the oppositely directed core extensions 15 to afford an unusually compact magnet, spool and core assembly.

45 To hold the aforesaid parts of the mechanism in fixed position with respect to the supporting plunger, I desirably secure the permanent magnet to the plunger top 9 by means which also clamp the two pole extensions 15 between the magnet and this plunger top, the magnet being disposed with the common medial plane of its shanks horizontal or normally parallel to the diaphragm. With this in mind, I am here showing a clamping plate 17 of non-magnetic material engaging the upper edge of the permanent magnet and secured to the plunger top 9 by vertical screws 18, thereby clamping the magnet and the core members jointly to the plunger or supporting 50 element. To prevent a tilting of the permanent magnet during such clamping, I desirably provide means such as a raised hump 19 on the plunger underhanging the bight of the permanent magnet.

65 Each core member of the apparatus,

namely each of the members comprising one of the vertical cores 12 and the corresponding pole extension 15, is desirably composed of laminations in the form of thin strips of soft iron which are initially punched as exact duplicates, then have their proposed vertical core portions secured tightly to each other, and thereafter have a bend formed in the assembled strips at the proposed juncture of the vertical core portion and the horizontal extension portion of the core member. I also desirably permit one of the fastening elements, such as the head of the rivet 20 of Fig. 5, to project slightly beyond the adjacent flat face of the core portion, thereby making it easier to slide the spool upon the core with the rivet head formed wedgingly against the adjacent wall of the bore of the spool and with the opposite side of the core in flatwise engagement with the adjacent wall of the said bore. I also desirably form oppositely directed shoulders 21 near the bottom of each core portion, whereby I provide a definitely positioned stop on which the corresponding magnet spool bottoms and also increase the width of the attached core extension so as to increase the magnetic flux from the permanent magnet to the core. In thus assembling the laminated strips into a core member, the strip portions composing the horizontal or core extension part will spread apart after the manner shown in Fig. 6 and their resiliency will tend to hold them somewhat separated. Consequently, this resiliency will afford an upward pressure against the adjacent magnet pole, thereby preventing an accidental loosening of the adjacent clamping screw 18 in case the apparatus is jarred.

To afford the needed circuit connections to the electro-magnet spools, I desirably mount upon the plunger top 9 a pair of wire terminal members 21, each of which is connected to a terminal wire of the double spooled electro-magnet and to one of the circuit wires 23 which extend into the casing through the lateral inlet 2.

With the parts thus arranged, it will be obvious that the entire actuating mechanism is mounted on the vertically movable plunger, so that the distance between the tips of the cores 12 and the diaphragm 3 can be adjusted by moving the plunger up and down within the casing. To effect such an adjusting movement without introducing lost motion, I interpose a spring 24 between the bottom 11 of the casing and the plunger top or supporting element 9, so that this spring will continuously tend to move the plunger together with the mechanism carried by the plunger towards the diaphragm. Then I provide a thread on the lower end of the plunger stem 10 for engagement with a nut 25 bearing against a lower portion of the casing. By turning this nut in one direction, the plunger and mechanism will be low-

ered against the resistance of the spring, while a turning of the nut in the opposite direction will permit the spring to raise the plunger correspondingly. This permits the desired adjustment to be made instantly in either direction, while the action of the spring overcomes any looseness of fit in the threaded connection between the plunger stem and the nut.

To prevent the plunger from rotating bodily, I provide suitable interengaging portions upon the casing and the plunger, these being here shown in the form of upwardly extending pins 26 cast on the bottom of the casing and each extending slidably through the corresponding vertical bore in the plunger top 9. The spring 24 is desirably of a bowed form with a central perforation through which the plunger stem extends, and the same pins 26 which prevent the plunger from rotating are desirably placed close to one edge of the spring so as to prevent the spring from rotating about the plunger stem. Thus arranged, the pins 26 prevent the spring from rotating into contact with the lower portions of the wire terminal members and also prevent the plunger top from rotating so as to bring the wire terminals out of proper relation to the wire inlet of the casing.

In addition to affording a simple means for adjusting the diaphragm, it will be seen from the drawings that a suitable fit between the plunger stem and the bore in which it slides will prevent a tilting of the mechanism, thereby maintaining the tips of the cores 12 parallel to the normal plane of the diaphragm throughout the adjusting movement. It will also be evident that the entire mechanism can be assembled upon the plunger before the latter is inserted in the casing, thereby greatly facilitating the assembly. However, while I have illustrated and described my invention in an embodiment including desirable shapes of the various parts, I do not wish to be limited to these shapes or to the details of the construction and arrangement thus disclosed, since many modifications might obviously be made without departing either from the spirit of my invention or from the appended claims.

I claim as my invention:—

1. In a telephonic receiver, a pair of magnet spools, a pair of magnet cores of angular longitudinal section each having one leg thereof extending through one of the spools, each of the cores being composed by superposed flat strips secured to each other in their said legs, and a magnet having its poles respectively in engagement with the other legs of the magnet cores, in combination with means for clamping the magnet poles against the magnet core legs engaged by them, the portions of the superposed strips forming the last named legs being unsecured to each other and the strips having inherent resiliency tending to space the said strip portions apart,

the said resiliency acting counter to the clamping means and serving to lock the clamping means against loosening.

2. In a telephonic receiver, the combination with a permanent magnet, of a magnet core comprising a plurality of superposed flat strips bent flatwise of the strips to an angular section so as to form two legs, one of the legs tightly engaging a pole of the magnet; a magnet spool through the bore of which the other leg of the magnet core extends; and a fastening element extending through the portions of the strips within the said bore for securing the strips to one another; the leg extending through the said bore having one face thereof in engagement with a wall of the bore, the fastening element projecting beyond the opposite face of the last named leg into engagement with the opposite wall of the bore so as to wedge this leg in the bore, thereby holding the spool in fixed position with respect to the magnet.

3. In a telephone receiver, a bi-part casing, a diaphragm having its edges secured between the two parts of said casing, a telephone unit comprising a bar of solenoid coils, angular laminated pole pieces extending into said coils, and a permanent magnet having its opposite poles engaging said laminated pole pieces in said casing having a plunger connected thereto and extending through said casing, a leaf spring disposed between said unit and said casing and having said plunger extending therethrough, said leaf spring tending to force said unit against said diaphragm, and means for withdrawing said plunger through the casing against the action of said spring to move the unit away from said diaphragm.

Signed at Chicago, Illinois, February 12th, 1925.
